(57) **CLAIM**

The ornamental design for a window track, as shown and described.

DESCRIPTION

FIG. 1 is a side perspective view of a first embodiment of a window track showing my new design;

FIG. 2 is a front-end view thereof;

FIG. 3 is a right-side view thereof;

FIG. 4 is a left-side view thereof;

FIG. 5 is a top view thereof, the bottom view being a mirror image thereof;

FIG. 6 is a front end view thereof, showing the window track of FIG. 1 in an environment of use;

FIG. 7 is another front-end view thereof, showing the window track of FIG. 1 in an environment of use;

FIG. 8 is a side perspective view thereof, showing the window track of FIG. 1 in an environment of use;

FIG. 9 is another side perspective view thereof, showing the window track of FIG. 1 in an environment of use;

FIG. 10 is a side perspective view of a second embodiment of the window track showing my new design.

FIG. 11 is a front-end view thereof;

FIG. 12 is a right-side view thereof;

FIG. 13 is a left-side view thereof; and,

FIG. 14 is a top-side view thereof, a bottom-side view (not shown) is a mirror image thereof.

The broken lines in the drawings illustrate environmental subject matter only and form no part of the claimed design. The window track in FIGS. 1 through 5 has been shown broken away for convenience of illustration. The window track is fully shown in FIGS. 8 and 9 in a smaller scale. The window track in FIGS. 10 through 14 has been shown with a symbolic break in its length. The appearance of any portion of the window track between the breaks form no part of the claimed design.
